UNITED STATES PATENT OFFICE.

FRANK GARDNER, OF DALLAS, TEXAS.

PUMP JACK.

Application filed October 9, 1924. Serial No. 742,557.

To all whom it may concern:

Be it known that I, FRANK GARDNER, a citizen of the United States of America, residing at Dallas, in the county of Dallas and States of Texas, have invented certain new and useful Improvements in Pump Jacks, of which the following is a specification.

My invention relates to new and useful 10 improvements in pump jacks.

The object of the invention is to provide a pump jack for pumping wells which is arranged to reciprocate the polish rod and to compensate for the swing of the beam in 15 a new and novel manner, whereby the polish rod is given a free perpendicular stroke.

A particular object of the invention is to provide a jack equipped with a toggle joint and a link co-operating with a pivoted Samson post and a pivoted beam to impart a perpendicular stroke to the polish rod.

An important feature is to provide a pump of simplified construction in which the number of parts are reduced to a minimum.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is an enlarged elevation of a pump jack constructed in accordance with my invention,

Fig. 2 is a plan view of the same,

Fig. 3 is a front elevation of the jack,

Fig. 4 is an enlarged sectional view of one of the knuckles of the toggle joint,

Fig. 5 is an enlarged cross-sectional view taken on the line 5—5 of Fig. 1,

Fig. 6 is a partial rear elevation, and

Fig. 7 is a side elevation of a modified form.

In the drawings the numeral 10 designates the base or sills which may be formed of a pair of I-beams spaced apart and suitably connected. A yoke clamp 11 is provided at the front end of the base for engaging the casing at the well and in use the base is suitably anchored. A transverse fulcrum bracket 12 is secured across the rear end of the sills and has up-turned ears 13.

A Samson post 14 formed of channel members has its lower ends fulcrumed on a bolt 15 passing through the ears. The channel

members are bent to converge inwardly from a point just above the ears to about half-way the height of the post, the upper extensions being parallel.

A pivot bolt 16 extends through the members of the posts intermediate the ends of said members and brace arms 17 on each side of the post have their upper ends pivoted on said bolt. Complementary brace arms 18 have their lower ends pivoted to brackets 19 on the base sills; while their upper ends are connected with the lower ends of the braces 17 by knuckle joints 20 within clevis 21 on the lower ends of links 22. Hangers 23 are fastened to the channel members of a beam 24. Each link has its upper end pivoted to one of the hangers.

The beam 24 is pivoted in the upper ends of the post 14 upon a cross bolt 25 and extends forwardly. At the forward end of the beam is mounted a polish rod clamp 26 journaled in bearing boxes 27 fastened on the members of the beam. The polish rod A of the well is secured in the clamp in the usual manner.

It will be apparent that the link 22, knuckle joint 20 and braces 17 and 18 on each side form a toggle joint, which is broken or opened whenever the beam 24 is swung from a normally horizontal position. This permits the Samson post to swing, whereby the beam 24 is moved longitudinally to compensate for the swing of the clamp 26, thus relieving any tendency to bend the polish rod. So long as the beam is in a horizontal position the braces 17 and 18 will be aligned and the Samson post will be perpendicular at substantially right angles to both beam and the base.

A rocker 28 having the general form of a bell crank lever has a saddle 29 near its rear end and adjacent the swing post 30 of the rocker. A bearing box 31 mounted on the base 10 supports the saddle. The rocker may be of any approved type and no claim is made individually to the same. The type illustrated is in common use. A pitman 32 journaled on the forward end of the rocker has its upper end pivoted to the underside of the beam in a cap bearing 33. The post 30 has a stirrup mounting 34 at its upper end for the usual D-stirrup of the connecting rod (not shown).

In operating the jack the rocker 28 is swung by the connecting rod from the pumping power. When the rod is pulled the post

30 is swung rearwardly, whereby the pitman 32 is elevated and the beam 24 swung upwardly. When the pull on the rod is relieved the weight of the sucker and polish 5 rods will swing the beam 24 down through its down stroke. When the beam is swung upward from the horizontal the link 22 will break the toggle joint upwardly so that the Samson post may swing and when the beam 10 is swung downward the toggle is broken downwardly also permitting the post to swing. The clamp 26 may, by this arrangement, follow the perpendicular path of the polish rod without bending or distorting the 15 same.

In Fig. 7 I have shown a modified form wherein a long stroke is secured. The structure is largely the same except that in place of the polish rod clamp 26, I have mounted 20 bearing boxes 34 on the forward ends of the members of the beam 24 for supporting a cross shaft 35 on which a sprocket wheel 36 is mounted. A sprocket chain 37 passing over the wheel has one end fastened as at 25 39 between the beams of the base 10. The other end of the chain carries a clamp 40 which is secured to the polish rod A.

A counterbalancing beam 41 extends from the rear end of the beam 24 and has 30 a hanger 42 suspending a weight 43 from the outer end of the beam 41. When the beam 24 is swung the sprocket wheel 36 will revolve and will move relatively along the sprocket chain 37, this increased leverage 35 will cause the clamp 40 carrying the polish rod to travel a greater distance than the clamp 26, thus giving a longer stroke. The weight 43 will counterbalance the load during the stroke.

40 It is to be understood that the invention is directed to the toggle joint and the swinging Samson post and the structure of the base, Samson post and beam are all subject to variation within the scope of 45 the appended claims. The base, Samson post and the toggle constitute what is known in the oil fields as a jack frame.

What I claim, is:

1. In a pump jack, a base, a Samson post 50 pivoted to the base, a beam pivoted at one end to the post, bracing members pivotally connected at their outer ends to the base and post respectively and at their inner ends to each other, a link pivotally connected at 55 one end to the pivotally connected ends of the bracing members and at its other end to the beam at a point adjacent to the pivoted end of the latter, a rocker, and a pitman connected to the rocker and to the beam, the 60 point of connection of the pitman to the beam being between the free end of the beam and the point of connection of the link therewith.

2. In a pump jack, a horizontal base, a 65 Samson post pivoted on the base, a beam

journaled on the post, a three-element direct toggle joint connection between the base, post and beam, and means separate from and independent of said toggle joint connection for swinging the beam. 70

3. In a pump jack of the character described, a base, a Samson post pivoted on the base, a beam journaled on the post, a three-element toggle joint bracing and actuating connection between the base, post and beam, including a pair of normally aligned brace members extending across the angle between the base and post and pivotally connected at their inner ends to each other and at their outer ends to the base and post respectively, and means separate from and independent of said toggle joint bracing and actuating connection for swinging the beam. 75

4. In a pump jack of the character described, a base, a Samson post pivoted on the base, a beam journaled on the post, normally aligned brace members extending across the angle between the base and post, said brace members having their inner ends hinged together and having their outer ends pivoted to the base and post, a link having one end pivoted to the beam and the other end pivoted to the brace members at their hinge connection to form a toggle, and means for swinging the beam. 80

5. As a sub-combination in a pump jack, a base, a Samson post pivoted on the base, a beam journaled on the post, normally aligned brace members extending across the angle between the base and post and having their inner ends pivoted to each other and their outer ends pivoted to the base and post respectively, and a link pivoted to the beam and said brace members. 100

6. As a sub-combination in a pump jack, a base, a Samson post pivoted on the base, a beam journaled on the post, normally aligned brace members of substantially equal length extending across the angle between the base and the post and having their inner ends hinged together and having their outer ends pivoted to the base and post, a link having one end pivoted to the beam and the other end pivoted to the brace members at their hinge connection to form a toggle. 105

7. In a pump jack of the character described, a base, a Samson post pivoted on the base, a beam journaled on the post, inclined brace members extending from the base to the post across the angle formed by the base and post and pivoted at their outer ends to the base and post a knuckle joint connecting the brace members, a link pivoted at its upper end to the beam and pivoted to the knuckle joint at its lower end, and means for swinging the beam. 110

8. In a pump jack of the character described, a longitudinal base, a Samson post comprising upright elements spaced apart and pivoted on the base, a beam journaled 125

- on the post between the elements thereof, inclined brace members pivoted on each side of the jack to the elements of the post and to the base, knuckle joints connecting the 5 brace members between their pivot points, links pivoted at their upper ends to the beam and connected at their lower ends with the knuckle joints to form toggles, and means for swinging the beam.
- 10 9. In a pump jack of the character described, the combination of a base, a bracket on the base, a Samson post pivoted on the bracket, a beam journaled on the upper end of the post, a pair of brace members pivoted 15 to the post between the base and the beam, a second pair of brace members pivoted to the base, said brace members being inclined, knuckle joints connecting the members of one pair with those of the other pair, hangers on the beam, links pivoted at their upper ends to the hangers, clevises connecting the lower ends of the links with the knuckle joints, a rocker mounted on the base, and a pitman mounted on the rocker and pivoted to the beam.
- 15 20 10. In a pump jack of the character described, the combination of a base, a bracket 25 on the base, a Samson post pivoted on the bracket, a beam journaled on the upper end of the post, a pair of brace members pivoted to the post between the base and the beam, a second pair of brace members pivoted to 30 the base, said brace members being inclined, knuckle joints connecting the members of one pair with those of the other pair, hangers on the beam, links pivoted at their upper ends to the hangers, clevises connect- 35 ing the lower ends of the links with the knuckle joints, a rocker mounted on the base, and a pitman mounted on the rocker and pivoted to the beam.

In testimony whereof I affix my signature.

FRANK GARDNER.
